(57) **CLAIM**

The ornamental design for the sunglasses that stick to a sun cap, substantially as shown and described.

DESCRIPTION

FIG. 1 is a front view of the sunglasses that stick to a sun cap;

FIG. 2 is a rear view of the sunglasses that stick to a sun cap of FIG. 1;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a perspective view of the sunglasses that stick to a sun cap that shows how the sunglasses are to be attached to a sun cap; and,

FIG. 9 is an enlarged, partial perspective of the circled area 9 of FIG. 8.

The broken line depiction of environmental structure is for illustrative purposes only and forms no part of the claimed design.
